UNITED STATES PATENT OFFICE.

WILLIAM R. QUEHL, OF ST. LOUIS, MISSOURI; CATHRYN E. QUEHL ADMINISTRATRIX
OF SAID WILLIAM R. QUEHL, DECEASED.

STEPLADDER.

Application filed December 23, 1922. Serial No. 608,695.

To all whom it may concern:

Be it known that I, WILLIAM R. QUEHL, a citizen of the United States, residing at St. Louis, in the county of St. Louis and 5 State of Missouri, have invented new and useful Improvements in Stepladders, of which the following is a specification.

This invention contemplates certain improvements in folding step ladders which 10 facilitate folding thereof, and also allow the ladder to be materially reduced in size, so that it will occupy but little space when not in use.

The nature and advantages of the invention will be better understood when the following detailed description is read in connection with the accompanying drawings, the invention residing in the combination, construction and arrangement of parts as 20 claimed.

In the drawings forming part of this application, like numerals of reference indicate similar parts in the several views, and wherein:

25 Figure 1 is a side elevation of a ladder in position for use.

Figure 2 is a front elevation thereof.

Figure 3 is a rear elevation.

30 Figure 4 is a side elevation of the ladder folded.

Figure 5 is a sectional view taken on the line 5—5 of Figure 2.

Figure 6 is a perspective of one of the elements embodied in the invention.

35 Figure 7 is a similar view of one of the step sections.

Referring to the drawings in detail, 10 indicates the sides of the ladder which are properly spaced apart, and connected by the steps as shown. The sides have associated therewith supporting legs 11 which are pivotally associated with the sides at the upper ends thereof as at 12. The legs 11 are connected together by transversely disposed bracing elements, each of which includes pivotally connected sections 12, and these bracing elements are connected together by a vertically disposed bar 14, so that said elements can be folded or extended in unison. The bar 14 has associated therewith a hand grip 15 for the purpose of manipulating the bar in a manner and for a purpose to be more fully described, and in connection with which purpose, the bar 14 is provided with 55 a pin 16.

The steps each include two sections which are normally arranged in end to end relation, and the sections are pivotally connected together, so that when the sections are broken at this point, they can be arranged vertically and parallel in folded positions. Each section 17 and 17' is slotted midway its ends to receive the extensions 18 formed by the slots for a fitting engagement with each other, the construction being such that the steps can be broken to be folded in the manner stated, and at the same time afford the desired strength and rigidity when extended for use. The outer end of each section is pivotally associated 60 with the sides 10 of the ladder, and each section is provided with a hanger of the construction shown in Figures 6 and 7.

Each hanger is designed to embrace one side of the ladder and being substantially 75 of U-shaped formation as shown. The body of the hanger is indicated at 19, while the parallel portions are indicated at 20 and 21 respectively. The portion 20 is provided with a slot 22 to loosely receive trunnion 23 80 which projects from one side of the adjacent step section, while the portion 21 is provided with an enlarged opening 24 to receive an elongated lug 25 projecting from the opposite side of the adjacent step section, and slightly to one side of the lug 23. This construction provides for a pivotal connection 85 between the step sections and the sides 10 of the ladder. When the steps are arranged for use, the lugs 25 are arranged horizontally in the openings 24 of their hangers, when the steps are folded the lugs are turned within the opening 24 and are then arranged vertically to assist in holding the step sections in parallelism when folded. In addition to the pivotal movement provided for the steps, the construction allows the steps to slightly rock within the openings 24, so that when the steps are folded the sections will be brought to position to lie 90 directly behind the sides 10. The steps are all connected by a vertically disposed bar 26 which is provided with an opening 27 to receive the pin 16 above referred to, when the legs 11 are swung into the direction of the side members 10. After the pin 16 has been positioned within the opening 27, the handle 15 associated with the bar 14 is taken hold of and the said bar 14 and bar 26 100 moved together in an upward direction, 105 110

thereby collapsing or folding all of the steps in unison. Manifestly as the steps are thus folded, the sides 10 are brought into closely related positions and the ladder in its entirety materially reduced in size so as to occupy but a minimum of space when not in use. One leg 11 is provided with an eye member 28 which accommodates a hook 29 carried by one of the sides 10, and utilized to hold the ladder folded. Hinged brace members 26' are connected with the sides 10 and 11 to hold the parts against movement when the ladder is in operative position.

15 While it is believed that from the foregoing description, the nature and advantages of the invention will be readily apparent, I desire to have it understood that I do not limit myself to what is herein shown and described and that such changes may be resorted to when desired as fall within the scope of what is claimed.

What I claim is:

1. A ladder including a pair of sections 25 hingedly connected together at one end, steps carried by one of the sections and each including hingedly connected sections, brace members pivotally connecting the sides of the other section and each including a pair 30 of sections hingedly connected together, longitudinally shiftable bars connected with the steps and brace members at their hinged connections, one of the bars being provided with an opening and a pin carried by the 35 other bar and adapted to be received in the opening, and a handle on one of the bars whereby to shift both bars longitudinally to break the hinged connection of the steps and brace members to collapse the ladder.
- 40 2. A ladder including a frame, a plurality of steps each provided with a hinged joint intermediate its ends, brackets carried by the frame each having an elongated opening at one side thereof, a trunnion carried by 45 each end of each of the steps and journaled in the brackets, a laterally projecting rectangular extension extending from the opposite side of each end of each of the steps and accommodated in the respective elongated opening.
- 50 3. A step ladder including sides spaced

apart, steps, each including two pivotally connected sections normally arranged in end to end relation and pivotally connected together, a pivotal connection between each section and the adjacent side members whereby said sections can be folded in parallelism and the side members folded closely together, a bar connecting all of said steps and movable to simultaneously fold the ladder, supporting legs pivoted to the side members, sectional bracing elements connecting said legs, a bar connecting said bracing elements and adapted to be arranged parallel with and connected to the 65 first mentioned bar, and utilized to adjust the ladder for the purpose specified.

4. A step ladder including spaced side members, steps, each including two sections normally arranged in end to end relation 70 and pivotally connected together, a pin projecting from one side of each section, a lug projecting from the other side of each section, hangers for each step, said hangers being designed to embrace the side members 75 of the ladder and having openings for receiving the respective pin and lug, whereby said steps can be folded in parallelism between said side members, a bar connecting all of the steps, supporting legs, bracing elements connecting the legs, a bar connecting said bracing elements, and means for connecting the bars for simultaneous adjustment as and for the purpose specified.

5. A step ladder including spaced side members, steps, each including pivotally connected sections adapted to be folded in parallelism between the side members, hangers for said steps, a pin projecting from one side of each section, a lug projecting 90 from the other side of the section, and to one side of said pin, each hanger being substantially U-shaped for straddling the adjacent side member of the ladder, said hangers each having spaced openings pivotally receiving the adjacent pin and lug, a bar connecting all of the steps, for folding said steps in unison, and supporting legs for said side members.

In testimony whereof I affix my signature.

WILLIAM R. QUEHL.
